US00D786036S

(12) **United States Design Patent** (10) **Patent No.:** **US D786,036 S**
(45) **Date of Patent:** **** May 9, 2017**

(54) **SNIP**

(71) Applicant: **Fiskars Brands, Inc.**, Madison, WI (US)

(72) Inventors: **Colin Roberts**, Madison, WI (US); **Jens Housley**, Stoughton, WI (US)

(73) Assignee: **Fiskars Brands, Inc.**, Middleton, WI (US)

(**) Term: **15 Years**

(21) Appl. No.: **29/548,479**

(22) Filed: **Dec. 14, 2015**

(51) **LOC (10) Cl.** **08-05**

(52) **U.S. Cl.**

USPC **D8/52; D8/57**

(58) **Field of Classification Search**

USPC D8/4, 5, 51–58

CPC B26B 13/00; B26B 13/06; B26B 13/12; B26B 13/22; B26B 13/24; B26B 17/00

See application file for complete search history.

Primary Examiner — Deanna L Pratt

(74) *Attorney, Agent, or Firm* — Foley & Lardner LLP

(57) **CLAIM**

We claim the ornamental design for a snip, as shown and described.

DESCRIPTION

FIG. 1 is a front perspective view from above of the claimed design according to one embodiment;

FIG. 2 is a front side view of the claimed design of FIG. 1; FIG. 3 is a rear side view of the claimed design of FIG. 1; FIG. 4 is a top view of the claimed design of FIG. 1; FIG. 5 is a bottom view of the claimed design of FIG. 1; FIG. 6 is a left side view of the claimed design of FIG. 1; and,

FIG. 7 is a right side view of the claimed design of FIG. 1. Any portion of the article depicted in broken lines forms no part of the claimed design. Broken lines formed by equal length dashes show unclaimed portions of the design.

1 Claim, 5 Drawing Sheets
